UNITED STATES PATENT OFFICE.

CHARLES B. ROBERTSON, OF COLUMBUS, OHIO.

STREET-CLEANING MACHINE.

1,203,130.

Specification of Letters Patent.

Patented Oct. 31, 1916.

Application filed November 4, 1915. Serial No. 59,633.

To all whom it may concern:

Be it known that I, CHARLES B. ROBERTSON, a citizen of the United States, residing at Columbus, in the county of Franklin and State of Ohio, have invented a new and useful Street-Cleaning Machine, of which the following is a specification.

The device forming the subject matter of this application is a street cleaning machine, and one object of the present invention is to provide novel means for blowing air to the rear of rotating brushes and for applying a suction in front of said brushes thereby to effect a thorough cleaning of the surface over which the brushes pass.

Another object of the invention is to provide novel means for supporting the brush casings.

A further object of the invention is to improve the suction and discharge mechanism.

The invention aims to improve the collecting receptacle and parts adjacent thereto.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing:—Figure 1 shows the invention in side elevation, parts appearing in section; Fig. 2 is a horizontal section taken in a plane adjacent the platform portion of the vehicle; Fig. 3 is a fragmental elevation showing one of the brushes; Fig. 4 is a sectional detail of one of the brush casings; Fig. 5 is a side elevation of the brush casing; Fig. 6 is a sectional detail illustrating one of the yieldable couplings employed in various parts of the machine.

In carrying out the present invention there is provided a vehicle embodying a platform 1 supported on ground wheels 2 and 3. Mounted on the platform 1 is an engine 4 operatively connected by means of a belt 5 with the shaft 49 of a combined suction and blower device 6 mounted on the platform 1. Communicating with the cas-

ing of the suction and blower device 6 is a discharge conduit 7 opening as shown at 10 into one side of a separator 8 in the top of which is located an open ended flue 9. The separator 8 embodies a tapered lower end 11 received in an inverted funnel 12 disposed in the top of a dust receptacle 14 mounted on wheels 15, detachable connections 16 being employed for uniting the dust receptacle 14 with the frame work of the main vehicle, so that these parts may be drawn along together. In the top of the dust receptacle 14 is a screened opening 17 which avoids too great a pressure within the dust receptacle. At its rear end, the dust receptacle 14 may be provided with a hingedly mounted clean out door 18.

The casing of the suction and blower device 6 communicates with a transverse manifold 19 having rearwardly extended necks 75 20 united by swivel connections 21 with pipes 22 entering brush casings 23 near to the lower forward portions thereof. Disposed upon the sides of the brush casings 23 are guides 24 receiving slides 25 carrying bearings 26 in which are journaled shafts 27 carrying brushes 28, the shafts 27 carrying external closure plates 44 bridging the space between the guides 24.

Foot plates 43 are mounted on the upper 85 portions of the brush casings 23 and to the foot plates are connected springs 33, the upper ends of which are attached to vertically adjustable rods 34 movable in abutments 36 and provided with nuts 35 bearing against 90 the abutments, the springs 33 constituting a means whereby the brush casings 23 may be partially supported yielding. The brush casings 23 are provided at their lower ends with openings. Secured to the brush casings 23 and extended across the forward ends of the openings are resilient strips 30 which are rearwardly inclined, rear strips 31 of a similar sort extending across the rear ends of the openings, and side strips 32 co-operating with the lateral edges of the openings in the brush casings. Levers 37 are fulcrumed on the platform 1 and are provided with latch mechanisms 38 adapted to coact with segments 39 on the platform 1. The levers are provided with arms 40 to which are connected chains 41 assembled with springs 42 connected at their lower ends with the foot plates 43 on the brush casings 23.

Disposed transversely of the frame of the 110

machine and supported on hangers 46 is a manifold 45 having a forwardly extended inlet 45^a in which operates a fan 55 secured to and driven by the shaft 49 of the blower 6. 5 A counter shaft 51 is journaled in brackets 52 on the machine frame and is operatively connected with the blower shaft 49 by means of belts 50. Belts 48 connect the counter shaft 51 with pulleys 47 on the ends of the brush shafts 27. Projecting from the manifold 45 are conduits 58 united by flexible, swiveled joints 59 of the sort hereinbefore described, with pipes 60 carried by the tops of the brush casings 23, the pipes 60 terminating in enlarged heads 61 extended downwardly around the forward faces of the brush casings 23 and terminating adjacent the surface of the ground, the outlets of the heads 61 being indicated at 62. 10 The driving trains are as follows:—The shaft 49 of the suction device and blower 6 is actuated from the engine 4 by means of the belt 5. From the shaft 49 of the blower and suction device 6, motion is transmitted 15 to the counter shaft 51 by means of the belts 50. The fan 55 is driven by the shaft 49. From the counter shaft 51 motion is transmitted to the brush shafts 27 by means of the belts 48. 20 In practical operation, as the structure is drawn forwardly, the several closure strips 30, 31 and 32 around the openings at the lower ends of the brush casings 23 travel in contact with the ground and thus substantially prevent a leakage of air into the brush casings. Air under pressure is discharged 25 from the blower manifold 45 by means of the heads 61 through the outlets 62 in the direction of the travel of the vehicle and to the rear of the brushes 28, the dust collected and agitated by the brushes being drawn 30 through the pipes 22 and the necks 20 into the manifold 19, the dust passing thence into the casing of the suction device and blower 6, from which the dust is discharged 35 by the conduit 7 into the separator 8. As the dust and air is projected into the separator 8 through the outlet 10 of the conduit 7 a whirling motion is given to the dust and air, the dust passing downwardly and the air passing upwardly out of the flue 9. The dust, passing downwardly, traverses the funnel-shaped end 11 of the separator 8 and is deposited in the dust receptacle 14. The 40 springs 33 constitute a means for partially supporting the brush casings 23 yieldingly, it being possible at any time to raise and lower the brush casings by manipulating the levers 37, motion being imparted to the brush casings by way of the chains 41 and the springs 42, the brush casings being held in adjusted positions by engaging the latch mechanisms 38 on the levers 37 with the segments 39. 45 Owing to the fact that the flexible cou-

plings 21 and 59 are employed at the points above indicated, the brush casings are permitted to have the necessary movements.

It is to be observed that the springs 33 and 42 constitute a means for upholding the brush casings 23 for yieldable up and down movement, and for yieldable horizontal movement. Because the closures at the lower ends of the casings comprise front strips 30, rear strips 31 and side strips 32, the said strips yield each independently of the other to maintain substantially, the continuity of the closure, independently of the movements of the casing.

Having thus described the invention, what is claimed is:—

1. In a device of the class described, a vehicle; a brush casing carried by the vehicle and having an opening in its bottom; means for assembling the casing with the vehicle for yieldable up and down movement, and for yieldable horizontal movement; a brush journaled for rotation in the casing; and a closure carried by the casing and located about the opening, the closure comprising front and rear strips and side strips, each of said strips being yieldable independently of the other to maintain substantially the continuity of the closure independently of the movements of the casing. 95

2. In a device of the class described, a vehicle; a brush casing carried thereby; a brush journaled in the casing; a dust receptacle carried by the vehicle; a combined suction and blower mechanism on the vehicle; a conduit leading from the suction and blower mechanism to the receptacle; a suction conduit leading from the suction and blower mechanism to the casing and having an intake opening located in front of the brush; a conduit communicating at one end with the atmosphere independently of the receptacle and opening at the other end into the casing to the rear of the brush; a blast-producing means in the last specified conduit; an engine on the vehicle; and means for connecting the engine with the brush, the suction and blower mechanism and the blast producing means. 100 105 110 115

3. In a device of the class described, a vehicle; a combined suction and blower device mounted on the vehicle and including a shaft; a conduit leading from the suction and blower device; a receptacle into which the conduit discharges; a brush casing carried by the vehicle; a brush journaled in the brush casing; a pipe leading from the forward portion of the brush casing to the suction and blower device; a counter shaft journaled on the vehicle; a connection between the counter shaft and the shaft of the suction and blower device; a connection between the counter shaft and the brush; a second blower casing mounted on the vehicle; a conduit leading from the second 120 125 130 135

blower casing to the brush casing and discharging into the brush casing behind the brush; and a blower cooperating with the second specified blower casing and mounted on the shaft of the suction and blower device.

In testimony that I claim the foregoing

as my own, I have hereto affixed my signature in the presence of two witnesses.

CHARLES B. ROBERTSON.
